United States Patent

Des. 241,928
Patented Oct. 19, 1976

241,928

BOAT

Philip C. Peterson, 2335 Walters,
Northbrook, Ill. 60062

Filed Sept. 15, 1975, Ser. No. 613,526

Term of patent 14 years

Int. Cl. D12—06

U.S. Cl. D12—62

FIG. 2

FIG. 1

FIG. 3

FIG. 4

FIG. 5

FIG. 1 is a right side elevational view of a boat embodying my new design (the left side elevational view is a mirror image of FIG. 1);

FIG. 2 is a top plan view of the boat;

FIG. 3 is a rear elevational view of the boat;

FIG. 4 is a front elevational view of the boat; and

FIG. 5 is a bottom plan view of the boat.

I claim:

The ornamental design for a boat, substantially as shown and described.
